UNITED STATES PATENT OFFICE.

RAYMOND C. BONNELL, OF ATLANTIC CITY, NEW JERSEY.

HORSESHOE.

1,079,285.

Specification of Letters Patent.

Patented Nov. 18, 1913.

Application filed December 17, 1912. Serial No. 737,297.

To all whom it may concern:

Be it known that I, RAYMOND C. BONNELL, a citizen of the United States, residing at Atlantic City, in the county of Atlantic and State of New Jersey, have invented a new and useful Horseshoe, of which the following is a specification.

One object of the present invention is to provide a supplemental horse shoe which 10 may be assembled with the shoe proper.

Another object of the invention is to provide a supplemental shoe comprising grips which will be peculiarly efficient in maintaining a hold upon the ground.

15 Another object of the invention is to provide novel means for connecting the grips with each other.

The invention aims, further, to provide novel means for assembling the grips with 20 the shoe proper.

It is within the scope of the invention to improve generally and to increase the utility of, devices of that type to which the present invention appertains.

25 With the foregoing and other objects in view which will appear as the description proceeds, the invention resides in the combination and arrangement of parts and in the details of construction hereinafter described and claimed, it being understood that changes in the precise embodiment of invention can be made within the scope of what is claimed without departing from the spirit of the invention.

35 In the drawing: Figure 1 shows the invention in perspective, applied to a shoe; Fig. 2 is a longitudinal section looking in the direction of the arrows 2 in Fig. 1; Fig. 3 is a longitudinal section looking in the direction of the arrows 3 in Fig. 1; and Fig. 4 is a transverse section on the line 4—4 of Fig. 1, looking in the direction of the arrows.

45 In carrying out the invention, a pair of grips are provided, the same consisting of quadri-lateral, centrally open frames. The frames comprise inner side bars 1 and 2, heels 3, toes 4 and 5 and outer side bars 6 and 7. Owing to the construction of the 50 frames, as above described, the frames will grip the ground with peculiar efficiency, the parts 4 and 5 limiting forward movement, the parts 3 limiting rearward movement, the tongue 12 limiting movement either forward or backward, and the parts 6, 1, 2, 7, 55 5, 4 and 3 limiting transverse movement.

The frames may be provided with calks 8 of any desired construction, the calks 8 in the present instance, although not of necessity, being located adjacent the rear portions of the heels 3 and adjacent the forward portions of the toes 4 and 5. The toes 4 and 5 terminate in clips 9 which preferably are long enough to extend upwardly across the edge of the shoe 10, and to bear upon the hoof. The heels 3 are provided at their rear extremities with clips 11 which preferably, engage the shoe 10 only.

Projecting from the inner side bar 1 of one frame is a transverse tongue 12. The 70 tongue 12 is received slidably in seats 14, formed in the inner side bar 2 and in the outer side bar 7 of the other frame. The inner side bars 1 and 2 of the frames are provided with bosses 15 through which extends a bolt 16 or like connecting element, the bolt 16 being equipped at its inner end with a nut 17 which is adapted to bear against the inner edge of the side bar 2 of one frame. Adjacent its forward end, the 75 inner side bar 1 of one frame is provided with an outstanding lug 18, into the forward edge of which is threaded a screw 19 provided with a head 20 which is adapted to bear against the rear edge of the forward 80 portion of the shoe proper 10.

In practical operation, the nut 17 is tightened on the bolt 16 so as to draw the grips or frames toward each other, so that the clips 9 and 11 will exercise their obvious 90 functions. The tongue 12, registering in the seats 14, serves to direct the relative movement between the frames when such movement is produced by the bolt 16 and the nut 17. By rotating the screw 19 until the head 95 20 bears against the inner edge of the forward portion of the shoe 10, the supplemental shoe will be crowded rearwardly, so that the clips 9 become effective. In this connection, it is to be noted that because 100 the tongue 12 is engaged in the seats 14, both frames which constitute the supplemental shoe, will be crowded rearwardly when the screw 19 is actuated.

Having thus described the invention, what 105 is claimed is:—

A shoe of the class described comprising a pair of centrally open frames and a clamping device connecting the frames; one frame being provided upon its inner edge with a 110 transverse tongue projecting within the contour of the other frame, and said other frame
